(57) **CLAIM**

The ornamental design for a “stock pot with lid and side handles,” as shown and described.

DESCRIPTION

FIG. 1 is a perspective view of the “stock pot with lid and side handles”, showing my new design;
FIG. 2 is a top plan view thereof.

FIG. 3 is a front elevation view of thereof; and,
FIG. 4 is a side elevation view thereof.

The broken line showings in FIGS. 1-4 are for illustrative purposes only, depicting the environment of the new design, forming no part thereof as claimed.
